UNITED STATES PATENT OFFICE.

ALFRED PINEL, OF QUINCY, MASSACHUSETTS.

BUSH-HAMMER.

No. 878,559.

Specification of Letters Patent.

Patented Feb. 11, 1908.

Application filed July 25, 1907. Serial No. 385,509.

To all whom it may concern:

Be it known that I, ALFRED PINEL, a citizen of the United States, and a resident of Quincy, in the county of Norfolk and State 5 of Massachusetts, have invented an Improvement in Bush-Hammers, of which the following description, in connection with the accompanying drawings, is a specification, like letters on the drawing representing like 10 parts.

This invention has for its object the production of a novel bush hammer for stone work, the hammer shown being designed more particularly for use in a power actuated 15 machine.

In bush hammers of this type different plans have been devised for holding the bits or cutting blades, as for instance by bolts passing through holes or notches in the bits 20 and through the sides of the head or casing, or by inclosing the shanks of the bits between the sides of the casing and interposing between one side of the casing and the bits a wedge tapered in the direction of its length, 25 with its smaller end uppermost.

The use of bolts is very objectionable for the holes or notches in the bits weaken the same, the rapid vibrational movement of the hammer in the machine setting up such 30 strains that the bits soon fracture between the bolt receiving openings, and in addition it is practically impossible to maintain the bolts tight in the head or casing.

With the wedge structures now in use the 35 operation of the hammer soon tends to loosen the wedge and disarrange the bits, it being either very difficult to maintain the wedge tight for any length of time, or the constant impact of the tool upon the stone causes the 40 wedge to break the casing or head.

In my present invention I have discarded altogether bolts or similar devices, thereby obviating the use of holes or notches in the bits, and I interpose between the bits and 45 the side of the head a wedge tapered in the direction of its length and also in the direction of its width, with its larger end uppermost.

By placing the larger end of the wedge 50 uppermost there is no possibility of the wedge dropping out when the hammer is in use, and by tapering also in the direction of its length, which is transverse to the length of the bits, a very slight blow with a hammer 55 will drive the wedge into place with sufficient force to firmly retain the bits in place.

I have so constructed and arranged the head of the hammer that its weight, the weight of the bits, and the weight of the device employed to retain them in operative 60 position is distributed substantially equally with relation to the longitudinal axis of the shank of the hammer.

The various novel features of my invention will be fully described in the subjoined specification and particularly pointed out in the 65 following claims.

Figure 1 in side elevation represents a bush hammer embodying my invention; Fig. 2 a lower end view of the hammer shown in 70 Fig. 1, and Fig. 3 a section in the line x, Fig. 1.

The head A of my novel bush hammer has a shank A' that is engaged in usual manner by the mechanical part of the machine employed to move the hammer in working the 75 same in dressing stone. The head is shown as forked, it presenting two depending legs or side walls a, a', and an upper or cross portion a². Viewing Fig. 1, it will be noticed

that the width of the metal from the corner 80 edge 3 in the diagonal dotted line 2,3 is greater than the width of the depending portions a, a' so that the cross portion a² is so strengthened that it cannot bend or fracture due to strains outwardly on the depending 85 portions a, a'. The inner side wall 4 of the depending portion a' is shown as substantially vertical, while the inner side wall 5 of the depending portion a is represented as inclined upwardly and outwardly, the width 90 of the depending portion a being slightly less than that of the downturned portion a'. The flat shanks of the bits B are shown as notched at their upper ends to leave projecting portions 6 that embrace the crossed part 95 a² of the head between the depending portions a, a', preventing any movement of the bits from front to rear of the head. In the space between the inner wall 5 of the depending portion a and the bit B next it, I insert a wedge C shown in Fig. 1 as tapered from its bottom to its top, said wedge, see Fig. 2, being also represented as tapered in the direction of its length.

In practice I have found that a wedge of 105 this form has the greatest holding capacity possible for a wedge, and as the wedge is driven by a slight blow in the direction of the arrow, Fig. 2, to lock the bits in the head, the lengthwise taper of the wedge, as well as 110 its width taper coact to more effectually hold the bits than though the taper of the wedge

- was but in one direction. I have so shaped the head as to counterbalance the weight of the wedge; or in other words, the portion a' of the head to the right of the dotted line x Fig. 1, substantially counterbalances the weight of that portion of said cross bar and the depending portion a at the left hand side of the series of bits, plus the weight of the wedge.
- 10 In practice, with bush hammers employed in machines where the hammer is moved by pneumatic power to strike the blow, the shank extended from the bit-holding part or head of the hammer frequently breaks and 15 the entire hammer has to be thrown away. To obviate the loss of the head I have made the shank detachable and have connected the latter with the head by means of a wedge. The bit holding portion or head is represented as provided at its top with a dove-tail groove presenting side walls h , h' , and the lower end of the shank is tapered to present walls m , m' that incline outwardly, but of less width than the distance between the side 25 walls h , h' , and the lower end of the shank is provided with a dowel-pin n that enters an elongated hole n^x , Fig. 1, in the top of the head at the bottom of the groove made therein. After placing the shank in the 30 groove, with the dowel-pin in the left hand end of the hole n^x , the shank is moved to the right, as in Fig. 1, and I drive a wedge p into the space between the wall h' and the tapered side m' of the lower end of the shank, thus 35 locking the shank firmly to the head, with the wall m held against the side wall h in the head. Whatever part of the shank is left unbroken may be readily removed by knocking out the wedge p , moving the shank part

to the left to disengage the sides m and h , 40 and then lifting out the shank part.

Having described my invention, what I claim as new and desire to secure by Letters Patent is:—

1. In a bush hammer, a head having a 45 shank and forked to present depending arms, the inner side wall of one of said arms being inclined upwardly and outwardly and extending from the rear to the front of the head, a series of flat bits inserted between the side 50 walls of the arms, and a wedge inserted between said inclined side wall and the face of the adjacent bit, the wedge increasing in thickness from its lower edge to its upper edge and also tapering in the direction of its 55 length from one to the other end, the double taper of the wedge locking the bits in the head both laterally and longitudinally.

2. In a bush hammer, a head having a 60 shank and forked to present depending arms, the inner side wall of one of said arms being inclined upwardly and outwardly and extending from the rear to the front of the head, a series of imperforate bits notched at 65 their upper ends to embrace the head at front and rear thereof, and a wedge tapered in the direction of its length and also from its lower to its upper edge and inserted between the inclined side wall and the flat face of the adjacent bit.

In testimony whereof, I have signed my name to this specification, in the presence of two subscribing witnesses.

ALFRED PINEL.
